In Cuba December 22, 1948

3 Claims. (Cl. 160—172)

1

This invention relates to improvements in means and devices in shutters for windows.

It is customary to have recourse to such devices for protection from window openings. These devices are of two distinct types, such as, for example, the conventional wooden or metal window shutters which are of a relatively heavy construction and which are provided with means for locking or fastening them to window frames; this type of window shutter providing a means of protection against cold, heat, hail-stones and protection from intrusion of burglars; the latter type of shutter being light, movable or stationary, flexible or rigid and composed of assembled preferably metallic narrow strips or louvers; the latter type being known in the trade as Venetian blinds. These window shutters are designed and used for protection of window panes from breakage by stones or hail-stones and for the prevention of excessive light from entering into an inhabited room.

It is an object of the present invention to provide a device for permitting one to shut windows for protection against intrusion by strangers.

Another object of this invention resides in the provision of means to regulate the amount of light rays to be admitted into an inhabited place.

Still another object of this invention resides in the provision of means to close or open and to regulate window shutters from the inside.

A further object of this invention is to provide the window shutters devoid of any parts composed of fabrics or any other woven or twisted vegetal material liable to deteriorate by ultraviolet rays of sunlight, deteriorating atmospheric dampness, rotting, putrefaction or deterioration by insects.

A yet further object of this invention resides in the provision of means for automatically fixing the window shutters or louvers in a desired position.

A still further object of this invention resides in the provision of means permitting to repair, change or attain with facility any parts comprising the invention.

These several advantageous objects are attained by the novel design, construction or arrangement of parts as hereinafter described and illustrated in the accompanying drawings constituting a feature of this disclosure in which:

Fig. I illustrates a side elevation of elements comprising the window shutter according to the present invention; this figure representing the said elements in suspended "open" position;

Fig. II illustrates the same elements, which are

2

represented in Fig. I, in a position they simultaneously acquire when the said window shutter is being lifted up;

Fig. III illustrates the lower part of the window shutter represented in isometric projection so as to give a clear and definite idea of the construction which is the object of the present invention;

Fig. IV illustrates the window shutter in closed position, providing a complete protection of the window opening from accessibility of undesirable intruders;

Fig. V illustrates the details of the collapsible strips which are used as a means of mutual attachment of the elements comprising the window shutter as disclosed in the present invention;

Fig. VI illustrates a schematic view of devices permitting vertical movement of the window shutter;

Fig. VIIa illustrates diagrammatically a disposition of devices represented by Fig. VI permitting vertical movement of the window shutter;

Fig. VII represents a cross section of the window-shutter frame in its lower part which carries the device for lifting and lowering of the window shutter and for the fixation of the shutter in a desired position;

Fig. VIII represents a cross section taken on line A—A' of Fig. VIIa, illustrating the details of the window shutter frame with appropriated grooves directing the movement of window shutter boards and allowing room for passage of the cables used for lifting and lowering the window shutter.

In the drawings, the numeral 1 represents window-shutter boards, blades or louvers, made of any suitable material. The length of the boards or louvers must be sufficient to accommodate the desired window opening and must be of such thickness and strength to provide sufficient protection against intruders. These boards or louvers are mutually suspended relative to each other by means of preferably metallic strips 2 which are of suitable size. These strips 2 consist of two parts, a long part 13 having an eccentric curved end 13a, and a short part 12. They

are provided at their extremities with small holes a for fixing them to the boards 1 by means of rivets p and with holes b for passage of small rivets r which join them together and permit axial rotation thereof in their movement when the shutter is being plied. The holes b of these strips 2 are set with a slight deviation 15 from their longitudinal center. This deviation is necessary to facilitate the plying movement. If these

holes b were on the same axial line, the effort

communicated to the strips 2 by the pulling cable would be transmitted directly to the axles and would increase the friction. A supplementary lateral effort applied to the joint axis of rotation would be necessary to disturb the direct action communicated by traction of cable 5 and to break the unstable equilibrium of forces acting along one direction. The deviation 15 of the joining holes from the center will permit the formation of an isosceles triangle with its apex formed by the axis of rotation. The force of traction transmitted by cable and lower board will act in a direct line toward the axis of rotation of the common short braces 12 and long braces 13, giving rise to a small torque proportional to the deviation 15 which will be able to start the movement of rotation for the joined braces.

As an additional means in providing the braces 13 and 12 with a capacity to maintain a proper position, a small preferably metallic knob 14 is fixed on the short brace 12 so as to arrest the eccentric extremity of the long brace 13. The braces 2, when fixed and assembled as described hereinabove, will permit the lifting of the window shutter boards 1 with ease without any additional effort and without any jamming. The window shutter boards or blades 1 have in the center of their extremities round axles 3 of suitable size. In the center of the axles 3 of the lower board 1a are fixed two metallic pins 4 provided with holes to fix the lifting cable 5 thereto. The window boards are assembled into a window shutter frame in such a manner that the small axles 3 of the boards 1 and the pins 4 slide along appropriate longitudinal grooves 30 in the frame, as shown in Fig. VIII. The pulling effort of cable 5 lifts the lower board by the said fixed metallic pins 4. The lower louver board 1a in its upward movement plies the braces 2 by which it is suspended to the next upper board. When the body of the lower board gets in contact with the next board, the upward movement plies the second set of braces 2 by which the second board is attached to the next one. This process is repeated till all boards 1 touch each other, thus taking up minimum space and making the window opening free. For closing the window opening, the process is reversed to that described hereinabove, that is, the boards 1 are released.

The disposition of cables for lifting and lowering the window shutter is schematically illustrated in Fig. VI. The device for lifting and lowering the shutter comprises the acting tambour or pulley 8 set on an axle 9a, of a handle 9, an idle reversing pulley 10 and five small rollers 11. All these parts are set in respective grooves of the frame 7. The thin steel cable 5 is directed in such a way that the portions 5a of cable 5 near the window opening W always move in the same direction (see Fig. VI), thereby assuring regular lifting or lowering of the blades in horizontal position (Fig. II). A detailed description of this disposition will be explained as follows: The frame of the window shutter consists of a lower member 16, right side vertical member 17, left side vertical member 18 and upper member 19. The lower member 16 has two recesses; one to provide room for acting tambour or drum 8 and the other to provide space for the idle reversing pulley 10. The recess for the acting tambour 8 is lined with a metal box 22 in which the tambour 8 is rotatable. This tambour is fixed on a metallic shaft 9a which passes through the thickness of the frame and protrudes a suitable length out of the frame. To prevent the

eventual wearing away of the wood, due to friction, a small metallic plate 23 is fixed to member 16 which also acts as a support and a bearing for shaft 9a. A handle 20 is pivoted to link 9b, the latter being pivoted to shaft 9a as clearly seen in Fig. VII.

As a very efficient, simple and a fool-proof means for fixing the window shutter in a desired position, the following device is used. A small metal tackle or screw 21 is set in a wooden plug 33 fixed in the wall 24. When not in use or released, the handle 20 is lowered by hand or by its own weight or straightened out by centrifugal force of rotation. The movement of the handle 10 in its transferred position is stopped by the said plug 21. The vertical members 17 and 18 of the window shutter frame may be composed of two parts, that is, the body proper and the inlays 25. When the inlays 25 are set in their assigned places, they will form a definite contour of the upright members with provision of appropriated grooves for cable 5 and axles or pins 3 for the boards, as illustrated in Fig. VIII. The upper member 19 of the frame has a cutout 19a covered by a board (not shown) to provide room for fixing the five small rollers 11 and to provide an appropriate passage for the cable 5. The members 17 and 18 have similar cutouts or recesses 17a and 18a for passage of the cable 5. The inlaid parts of the frame 7 are easily removed to permit access for inspection, replacement or repair of parts.

Beside the elementary movement to open or to shut the window opening by lifting or lowering the system of shutter boards or louvers, my device provides a very novel means of rotation of the said boards. The boards 1 are fixed in the corresponding grooves 30 of the window shutter frame by means of protuberant round axles 3. The shutter boards 1 are mutually fixed together by the two rows of jointed preferably metal strips 2 and cooperate together by their pivots or axles 3 in the hollow of the vertical grooves 30. The shutter boards could be swung in one direction or in another, to an extreme substantially vertical position. These boards could be set in position to touch each other and have their metal strips in alignment and in extended position. One of these extreme positions is represented in Fig. IV. This capacity of my device permits it to form a continuous stepped surface completely closing the window opening. The window shutter boards, joining each other in the above-mentioned position and having a common thickness, would represent a very solid and rugged protection for the dwelling against burglars or intruders.

From the foregoing description taken in connection with the accompanying drawings, it is apparent that an improved, simple, practical and inexpensive device for the purpose intended is provided. It is apparent however, that immaterial changes and modifications may be made by skilled persons without departing from the true spirit and scope of the invention as outlined in the appended claims.

Having thus described the invention, what is claimed as new, and desired to be secured by Letters Patent, is:

1. In a shutter for windows or the like, including a frame, boards mounted in said frame, said boards carrying central projections at their outer ends, guide channels on said frame receiving said projections, cable means engaging the projections of the lowest of said boards, mechanism for

raising said boards by exerting a pull upon said cable means; a linkage interconnecting all of said boards, said linkage comprising a pair of pivots flanking each of said projections and positioned adjacent the ends of the shorter sides of said boards, link means interconnecting corresponding pivots of adjacent boards, each of said link means including a pair of arms each mounted on a respective one of said pivots, and a pivotal connection between said arms halfway between the boards, said pivotal connection including a pivot and means limiting the outward movement of said pivot relative to the corresponding pivots of the adjacent boards to thereby permit folding of said boards toward said guide channels while preventing folding thereof in an outward direction.

2. In a shutter, the linkage according to claim 1 wherein each of said pairs of arms includes a longer and a shorter arm, said longer arm having an arcuate projecting portion extending beyond said pivot joining the pair of arms and eccentric relative to said pivot, the last mentioned means

including a stop on the shorter arm positioned to engage the arcuate projecting portion of the longer arm and preventing outward displacement of said arms beyond a position of relative longitudinal alignment of the arms.

3. In a shutter, the linkage according to claim 2 wherein said pivot joining the pair of arms is spaced inwardly from the pivots on said boards when the arms are in relative longitudinal alignment.

RUBEN BARBAT BETANCOURT.
